US00D957798S

(12) **United States Design Patent** (10) **Patent No.:** **US D957,798 S**
Han (45) **Date of Patent:** **** Jul. 19, 2022**

(54) **SHOE**
(71) Applicant: **NIKE, Inc.**, Beaverton, OR (US)
(72) Inventor: **Charles S. Han**, Portland, OR (US)
(73) Assignee: **NIKE, Inc.**, Beaverton, OR (US)
(**) Term: **15 Years**
(21) Appl. No.: **29/789,118**

(22) Filed: **Sep. 1, 2021**
(51) LOC (13) Cl. **02-04**
(52) U.S. Cl. **D2/947; D2/972**

(57) **CLAIM**

The ornamental design for a shoe, as shown and described.

DESCRIPTION

FIG. 1 is a side view of a shoe showing my new design; FIG. 2 is a rear perspective view thereof; FIG. 3 is a rear view thereof; FIG. 4 is an opposite side rear perspective view thereof; and, FIG. 5 is an opposite side view thereof. The claimed design is patentable over the references cited. The art of record not relied upon is cited as cumulative art.

1 Claim, 5 Drawing Sheets
